UNITED STATES PATENT OFFICE

WILLIAM T. HORMES, OF CATONSVILLE, MARYLAND

LOCKING DEVICE FOR DOORS

Application filed October 14, 1927. Serial No. 226,206.

This invention is a device for locking a door both at the top and the bottom portions thereof.

One of the objects of the invention is to provide a rectilinearly movable operating member located intermediate between locking detents, and so connected with the detents that movement of the operating member in either direction imparts simultaneous movements to the detents in opposite directions with respect to each other. A further object is to provide a locking device for doors so arranged that a constant pull in one direction will first unlock the door and then move it to open position. A further object is to provide means for yieldably maintaining a detent-operating device in a predetermined normal position, and connections between said operating device and the detents capable of also normally maintaining said detents in their locking positions. A further object is to provide key-operated locking means by which actuation of the operating means and movement of the detents may be prevented.

The invention will be hereinafter fully set forth and particularly pointed out in the claims.

In the accompanying drawings:—

Figure 1 is a front view illustrating a portion of a door, with the invention applied thereto. Figures 2 and 3 are detail views, respectively, illustrating the upper and lower locking detents. Figure 4 is a rear elevation illustrating the operating device and the locking means. Figure 5 is a longitudinal sectional view thereof. Figure 6 is a detail view illustrating a slight modification.

Referring to the drawing, 10 designates a door having a recess 11 formed in one stile thereof. The edge of said stile adjacent to said recess, is provided with a longitudinally disposed angular portion 12, which is covered by a protector strip 13 of angular cross section, secured to the stile in suitable manner, as by means of screws 13a. A portion of the inner face of the strip 13 is spaced from one face of the angular portion 12 to provide a guide way 14. Said door may be

movably supported in any suitable manner, but for illustrative purposes the invention is applied to a slidably mounted door for show cases, but is not limited to this type of door.

Covering the recess 11 is a carrier plate 15, 55 provided with rearwardly extended threaded bosses 16 which are engaged by suitable screws, not shown, to retain said plate 15, and the elements carried thereby, in position within the recess 11. Said face plate is provided with a depression 18, preferably of substantially hemispherical shape, a guide plate 19, and a guide lug 20. Concentrically positioned with respect to the depression 18 is a ring-like portion 21 of an operating lever 22, pivotally mounted on the plate 15 by means of a pin 23. Said operating lever is provided with a rearwardly extended lug 24, positioned to engage a supplemental lug 25 formed on the front face of a slidably operating member 26 which is guided by means of the plate 19 and the lug 20. A spring 27 encircling the rod-like extension of the member 26 which is guided by lug 20a, serves to normally force said member 26 upwardly to 75 maintain the lugs 24 and 25 in engagement. Removably secured at one end to the slidable member 26, as by means of a screw 29, is a laterally disposed arm 30, the free end of which extends beyond the adjacent edge of 80 the plate 15 across guide way 14, and is provided with holes 31 and 32 respectively. It will be observed that the lugs 24 and 25 cooperate to limit upward movement of the member 26, under the thrust of the spring 27, 85 and also to impart movement to said member 26 against the tension of said spring.

Pivottally mounted upon plates 35, suitably secured to the upper and lower ends of the angular portion 12, are detents 36 and 37. 90 The detent 36 is pivoted at one end 38 and provided at the other end with the locking shoulder 39. The detent 37 is pivoted intermediate between its ends as indicated at 40, one end being offset as indicated at 41, the other end being provided with the locking portion 42. Extending through the guide-way formed by the cut-away portion 12 and the strip 13 are two operating rods 43 and 44 respectively. The rod 43 has its lower 100 end

end bent and extended into the hole 31 of the arm 30. At its upper end it is provided with two right angular bends, as indicated at 45, and its extremity bent to engage a hole 46 in the detent 36, said hole being located intermediate between the ends of said detent. The upper end of the rod 44 is bent and extended into the hole 32 of the arm 30, the lower end being offset and its extremity bent 10 to engage a hole 47 in the offset portion 41 of the detent 37. By constructing the detents and operating rods as above described, only a very small space is required for the passage of the rods, and ample clearance is 15 provided for the detents without marring the appearance of the door.

For the purpose of locking the slidable member 26 against movement, any desired locking device may be employed. In the 20 drawing, is conventionally illustrated a well known form of lock consisting of a rotatable tumbler barrel 50, which is provided at its inner end with an actuator 51 having a peripheral enlargement 52 forming oppositely disposed shoulders. Said shoulders are positioned to engage pins 53 projecting from a locking member 54, rotatable upon said barrel. By inserting a key through a suitable slot in the barrel 50 and turning the same, the 25 shoulder 52 engages one or the other of the pins 53 and raises the locking member 54 to a position in the path of movement of the lower end of the slidable member 26, and prevents retraction thereof against the tension 30 of the spring 27. (See full lines, Figure 4). By reversely operating the member 51, the member 54 is allowed to drop as shown in dotted lines, Figure 4, thereby leaving the member 24 free to slide.

40 In operation, the parts are so mounted upon the edge of the door stile that when the door is moved to closed position the detents 36 and 37 will engage keeper plates in the door frame in a manner well understood in the art. As the door is closed, the detents are rocked upon their respective pivots, moving the rods 43 and 44 downwardly and imparting a corresponding movement to the arm 30 and the slidable member 26, against 45 the tension of the spring 27. It will be particularly noted that by connecting the wire 43 with the middle portion of the detent 36, and the rod 44 with the end of the detent 37, pivotal movement of said detents in opposite 50 directions will impart movement to the arm 30 and slidable member 26 in a common direction, i. e. against the tension of the spring 27. When it is desired to open the door, the operator places his finger into the depression 55 18 and grasps the ring-like portion 21 of the actuator 22, swinging said ring-like end outwardly upon the pivot 21, and through the engagement of the lugs 24 and 25, forcing the slidable member 26 downwardly against the 60 tension of the spring 27. This movement ex-

erts a pull upon the wire 43 and a push upon the wire 44, thereby moving them both in a common direction and rocking both detents to disengage the hook portions 42 from the complementary plates in the door frame. A continued pull upon the ring-like portion 19 in the same direction will result in swinging the door upon its hinges. If it is desired to lock the door in closed position, a key is inserted in the barrel 50 and the member 51 rotated so as to lift the lock member 54 upwardly to the position shown in full lines in Figure 4. When so positioned, said member 54 acts as an abutment to prevent longitudinal movement of the slidable member 26, and the door is therefore firmly locked in its closed position. When it is desired to unlock the door, the member 52 is rotated so as to bring the member 54 to the position shown in dotted lines Figure 4, allowing ample clearance for the slidable movement of the lower portion of the member 26.

55 In lieu of the two rods or wires 43 and 44, a single wire may be employed, as illustrated in Figure 6. Referring to said figure, 60 60 designates a wire having a spread portion 61 riveted to the arm 30. The ends of said wire where they are connected with the detents should be shaped to correspond to the shapes of wires 43 and 44 at the same positions.

65 The advantages of the invention will be readily apparent to those skilled in the art to which it belongs. It will be particularly noted that a simple means is provided by which locking detents may be conveniently positioned at the ends of a door stile and simultaneously operated from an intermediate point by means of a common actuator. Because of this arrangement, it is not necessary to cut very deeply into the stile of the door to provide the necessary clearance for the detents and the operating rods, and this is a particular advantage in connection with the doors of show cases and similar structures 70 where relatively thin stock is employed. It is to be understood, however, that the invention is not limited to this particular class of doors. A further important advantage is that the opposite pivotal movement is imparted to the slidable member, so that parts may be made to operate in a minimum of space. A further advantage is that simple means are provided by which a continued pull in one direction will first unlock the door and then move it to open position. By placing the guide strip over an angular cut-away portion of the stile, a simple guide is provided which gives a neat finish and yet at the same time, all of the working parts associated with the detents, are readily accessible.

75 Having thus explained the nature of the invention and described an operative manner of constructing and using the same, although 80

without attempting to set forth all of the forms in which it may be made, or all of the forms of its use, what is claimed is:—

1. The combination with a door having a recess in one of its stiles and a portion of the edge of said stile provided with a longitudinally disposed angular portion, and removable cover strips of angular cross section co-operating with said angular portion to provide guide-ways, of a carrier plate covering said recess and provided with a slidably mounted operating member extending into the recess, locking detents located at the top and the bottom of said stiles adjacent the ends of said guide-ways, links located in said guide-ways and independently connecting said detents with said arm so that they may move in unison therewith, a spring acting to retain said operating member in a predetermined normal position so as to hold said detents in a normal locking position, and an actuator engaging said operating member, said actuator being so connected that the door will first be unlocked and then moved to open position by a continued pull upon said actuator in one direction.

2. The combination with a movably mounted door, of a rectilinearly movable operating member supported thereby, detents pivoted to said door and spaced from said operating member in opposite directions, a link connection between said detents and said operating member, spring means acting to retain said operating member in a predetermined normal position so that said detents are maintained in their normal locking positions, and an actuator for imparting movement to said operating member in opposition to the tension of the spring means, said actuator being so connected that the door will first be unlocked and then moved to open position by a continued pull upon said actuator in one direction.

3. A locking device for doors comprising a slidably mounted operating member, a laterally extended arm rigidly secured at one end to said operating member, locking detents spaced from said arm in opposite directions and having their locking positions oppositely disposed with respect to each other, rods independently connecting the respective detents with the free end of said arm and independently of said operating member, so that movement imparted to the operating member in one direction will move the detents in opposite directions, a spring engaging said operating member so as to retain it in a predetermined normal position, and an actuator having means for normally maintaining an engagement with said operating member so as to move the same in a rectilinear path in opposition to the tension of said spring.

4. A locking device for doors comprising a slidably mounted operating member provided with a laterally extended rigid arm, a

spring acting upon said operating member to retain it in a predetermined normal position, locking detents relatively spaced in opposite directions with respect to said laterally extended arm, one detent being pivoted at one end and the other detent being pivoted intermediate between its ends, the locking portions of said detents being oppositely disposed with respect to each other, rods independently connecting the respective detents with said arm independently of said operating member so that the detents will be simultaneously moved in a direction in opposition to the tension of said spring, and a pivotally supported actuator having one extremity shaped to normally engage a complementary portion of said operating member so that movement of said actuator will impart rectilinear movement to said operating member.

5. A locking device for doors comprising a slidably mounted operating member provided with a lug, locking detents relatively spaced in opposite directions with respect to said slidably mounted member, one detent being provided with an offset end and pivotally supported at a position intermediate between its ends, the other detent being pivoted at one end, a link connecting the offset end of the first mentioned detent with said operating member, a second link independently connecting the middle portion of the other detent with said operating member, so that simultaneous movement of the links in either direction will impart movements to the detents in opposite directions, a spring acting to retain said operating member in a predetermined normal position, and a pivotally supported actuating member having one end provided with a lug normally engaging the lug of said operating member, so that movement in one direction may be imparted to said operating member by pivotal movement of said actuating member.

6. A locking device for doors comprising a slidably mounted operating member, a spring engaging said operating member so as to move it to a predetermined normal position, a laterally disposed arm having one end removably secured to said operating member and having holes in its other end, locking detents spaced in opposite directions from said arm and having their locking positions oppositely disposed with respect to each other, one of said detents being pivotally mounted at its end and the other pivotally mounted intermediate between its ends, rods each having one end in engagement with a hole in said arm, the other end of one of the rods being connected with the middle portion of the first mentioned detent and the other end of the second rod being connected with an arm of the second detent, so that the detents are separately connected with said laterally extended arm independently of the operating member, whereby simultaneous movement of

- the links in either direction will move the detents in opposite directions, and a pivotally mounted actuator engaging said slidable member so as to impart rectilinear movement thereto.
7. A locking device for doors comprising a slidably mounted operating member, a laterally extended arm secured to said member, locking detents spaced one above and 10 the other below said slidable member and having their locking positions oppositely disposed with respect to each other, rods separately connecting said detents with said arm independently of said operating member, so 15 that simultaneous movement of the rods in either direction in unison with said operating member will impart opposite movements to said detents, a spring acting to retain said operating member in a predetermined normal 20 position, a pivotally mounted actuator having means normally engaging said operating member and positioned to move said operating member in a rectilinear path in opposition to the tension of its spring, and means 25 operable at will and movable into the path of movement of said operating member so as to prevent movement thereof and simultaneously prevent pivotal movement of the detents.
8. In a locking device of the character described, the combination with a door having a recess in its front face and an actuator pivotally mounted in said recess so as to normally lie flush with the said face, of an operating member slidably supported by said door, and provided with an arm extended therefrom, said arm having a free end, locking detents spaced from said arm in opposite directions and having their locking positions 35 oppositely disposed with respect to each other, rods independently connecting the respective detents with the free end of said arm and independently of the operating member, so that movement imparted to the 40 operating member in one direction will move the detents in opposite directions, a spring engaging said operating member so as to retain it in a predetermined normal position, and actuator means carried by said actuator 45 and normally engaged with said operating member so that pivotal movement of the actuator member in one direction will move the operating member in opposition to the tension of said spring.
9. In testimony whereof I have hereunto set my hand.

WILLIAM T. HORMES.
